UNITED STATES PATENT OFFICE.

ALBERT T. SCHEIWER, OF ERIE, PENNSYLVANIA.

SCREW-DRIVER MECHANISM FOR INSULATOR SCREWS.

Application filed October 25, 1924. Serial No. 745,781.

This invention is designed to facilitate the driving of insulator screws. With the present device the screw may be driven from a rigid connection between the screw and 5 operating handle or through a ratchet mechanism which permits the driving in either direction. The forming of a ratchet mechanism in a practical manner in a device of this character forms the principal 10 subject matter of the invention.

The invention is illustrated in the accompanying drawings as follows:—

Fig. 1 shows a plan view of the device.

Fig. 2 a side elevation of the same partly 15 in section.

Fig. 3 a section on the line 3—3 in Figs. 1 and 2.

Fig. 4 a section on the line 4—4 in Fig. 3.

Figs. 5 and 6 similar sections with a different setting of the ratchet device.

Fig. 7 a detail view of the ratchet dog.

Fig. 8 a front elevation of the ratchet dog spring.

Fig. 9 a side elevation of the same spring.

Fig. 10 a bottom view of the ratchet dog 20 id holding cap.

Fig. 11 is a section on the line 11—11 in Fig. 1.

1 marks the insulator, 2 a screw in the 30 insulator, 3 a frame in which the screw driver is placed, 4 securing jaws adapted to engage the insulator, 5 a screw driver end adapted to engage the slot of the screw 2, and 6 a screw stem extending from the 35 screw driver point 5, said screw being slid- ily mounted in an opening 7 in the frame 3. The screw is engaged by a knurled nut 8 which extends through a slot 9 in the frame. By turning the nut 8 the screw 40 may be screwed down into the slot 5 and exert pressure on the insulator so as to clamp the whole device together in the jaws 4. A handle 10 is journaled on an extension 11 of the frame 3 and secured thereon by 45 screws 12 which extend into grooves 13 in the frame. The handle 10 has an opening 14 in alinement with the opening 7 and the upper end of the screw stem extends into this opening and is provided with square 50 faced ratchet teeth 15. The upper end of the handle has a socket 16 surrounding the opening 14 and the trunnion ends 17 of the ratchet pawls 17^a rest on the bottom of the socket 16 being located as chords to the arc 55 of the circle of the socket. There are two of these pawls oppositely placed as clearly

shown in Figs. 4 to 6. The pawl spring plates 18 have the trunnion ends 19 which also rest on the bottoms of the sockets 16, the plates being immediately back of the 60 pawls. These plates have the spring fingers 20, one being bent forwardly from the plate and the other rearwardly from the plate, one finger engaging the wall of the opening 14 and the other engaging a pawl 17^a. Thus 65 the pawl is yieldingly forced into engagement with the ratchet teeth 15. A cap 22 is arranged in the socket 16 and this cap has the slots 23 in which the upper ends of the pawls and spring plates are held. The cap 70 is secured in the socket by means of pins 24.

In order to disengage either pawl a cam ring 25 is journaled on the screw stem in an opening in the handle 10. The cam ring has a pin 26 which extends through a 75 slot 27 in the handle so that the ring may be swung manually to release either ratchet pawl desired. The ring is provided with a cam 28 integral with and projecting upwardly from the ring and this cam is shaped 80 to engage the lower ends of the pawls 17^a when the cam ring is swung in either one or the other direction, in one direction releasing one pawl and permitting the opposite pawl to operate so as to screw up the 85 screw, or when swung to the opposite direction effecting the engagement of the pawl for unscrewing a screw. Where the cam is in the central position as shown in Fig. 5 both pawls engage the ratchet and the 90 handle will be locked with the screw driver preventing its turning in either direction.

In operation the insulator with its screw is placed in the jaws, the screw driver moved down to engagement with the slot of the 95 screw and if it is desired to have the handle work on the ratchet the pin 26 is swung to the sides disengaging the ratchet locking the screw for a left-hand turn. If it is desired to remove the screw the device is put 100 in position in the manner above described and the opposite ratchet released, thus setting the ratchet mechanism to unscrew the screw, or if desired, both ratchet pawls may be in locking position by bringing the cam 105 ring to the central position.

What I claim as new is:—

1. In a screw driver mechanism for insulator screws, the combination of a driver; a frame in which the driver is mounted comprising hooks adapted to engage an insulator; a screw thread formed on the driver;

means for feeding the driver by means of the screw thread relatively to the frame; a handle; and a ratchet driving connection between the handle and driver.

- 5 2. In a screw driver mechanism for insulator screws, the combination of a driver; a frame in which the driver is mounted comprising hooks adapted to engage an insulator; a screw thread formed on the driver; 10 means for feeding the driver by means of the screw thread relatively to the frame; a handle; and a ratchet driving connection between the handle and driver comprising means for reversing the ratchet action.
- 15 3. In a screw driver mechanism for insulator screws, the combination of a driver; a frame in which the driver is mounted comprising hooks adapted to engage an insulator; a screw thread formed on the driver; 20 means for feeding the driver by means of the screw thread relatively to the frame;

a handle; and a ratchet driving connection between the handle and driver comprising means for locking the handle with the driver and for releasing the handle from the driver 25 in one direction.

4. In a screw driver mechanism for insulator screws, the combination of a driver; a frame in which the driver is mounted comprising hooks adapted to engage an insulator; a screw thread formed on the driver; means for feeding the driver by means of the screw thread relatively to the frame; a handle; and a ratchet driving connection between the handle and driver comprising 30 means for locking the handle with the driver and for releasing the handle from the driver in either direction.

In testimony whereof I have hereunto set my hand.

ALBERT T. SCHEIWER.
